H. W. HACKER.
PROOFING INKER.
APPLICATION FILED JUNE 8, 1917.

1,270,410.

Patented June 25, 1918.

UNITED STATES PATENT OFFICE.

HORACE W. HACKER, OF CHICAGO, ILLINOIS.

PROOFING-INKER.

1,270,410.

Specification of Letters Patent. Patented June 25, 1918.

Application filed June 8, 1917. Serial No. 173,484.

To all whom it may concern:

Be it known that I, HORACE W. HACKER, citizen of the United States, residing at Chicago, in the county of Cook and State 5 of Illinois, have invented a certain new and useful Improvement in Proofing-Inkers, of which the following is a full, clear, concise, and exact description.

My invention relates to hand operated 10 proofing inkers and has several objects and advantages in view. In accordance with one characteristic of the invention the inker includes a form inking roller, a frame in which said roller is mounted to turn, a handle upon the frame and at least one distributing roller and a mounting for the distributing roller that permits movement of this roller toward and from the form inking roller when the device is idle. In the 15 preferred embodiment of the invention there are provided openings in end portions of the frame between the form inking roller and the handle in which at least one end of the shaft of the distributing roller is mov- 20 able toward and from the handle and the form inking roller. These openings permit the distributing roller to move away from the form inking roller when the device is laid in an idle position whereby the lat- 25 ter roller is relieved of the pressure of the former roller when the proofing inker is at rest. The form inking rollers are usually made of impressionable composition which is likely to be injured if subjected to con- 30 tinued pressure of a distributing roller when the device is at rest, on which account the described arrangement of the distributing roller is of utility.

In accordance with another characteris- 40 tic of the invention the proofing inker, with or without a distributing roller or rollers, is provided with means whereby the inking roller will be maintained in an elevated position when the frame carrying it is laid upon a horizontal support, such as an inking plate with either side of the frame uppermost. By insuring the removal of the inking roller from contact with the inking plate or other support the roller will not 45 become flattened. In conjunction with this construction there is desirably employed structural means whereby the handle may also be elevated from the support when the frame is supported with at least one and 50 preferably either side uppermost. When the support happens to be an inking plate

the handle is kept clear therefrom so as not to be spotted with ink when the device is at rest.

While the form inking roller and the 60 handle are each preferably elevated out of contact when the device is at rest with either side of the handle frame uppermost, I do not wish to be limited to all of these characteristics.

65 I will explain my invention more fully by reference to the accompanying drawing showing the preferred embodiment thereof and in which Figure 1 is a side elevation of a hand operated proofing inker made in accordance with the preferred embodiment of the invention; Fig. 2 is a plan view of the structure shown in Fig. 1; Fig. 3 is a view on line 3—3 of Fig. 2; Fig. 4 illustrates a modification; and Fig. 5 diagrammatically 70 indicates a characteristic of construction.

75 Like parts are indicated by similar characters of reference throughout the different figures.

70 The inker of my invention includes a form inking roller 1 which is usually made of impressionable resilient composition of the kind known to those familiar with the art and to which the printing ink may readily be transferred from an inking plate 85 over which the form inking roller is passed and from which ink may readily be transferred to the form that is to be inked. This form inking roller is provided with a shaft 2 which is mounted to turn in the ends 3 of 90 a suitable frame to which frame a handle is supplied, the handle 4 shown being in the form of a separately constructed gripping piece that is attached to the middle member 5 of the frame by means of the screw 6. 95 One side of the frame carries projections 7 and 8 in the construction shown in Figs. 1 to 3 inclusive while the opposite side of the frame carries projections 9 and 10. The projections upon each side of the frame are 100 upon opposite sides of the center of gravity of the device, such center of gravity being upon one side of the axis of rotation of the form inking roller. The said projections are upon the same side of the axis of the 105 form inking roller with the center of gravity and the center of gravity is between the axis of the roller 1 and the projections 8 and 10 whereas the projections 7 and 9 are between the axis of the roller 1 and the 110 center of gravity. By this arrangement both the roller and the handle will be ele-

vated when the device is rested upon a horizontal support with either of said sides of the frame uppermost and while all of these results are desirable with either side of the frame uppermost, I do not wish to be limited to the employment of all projections 7, 8, 9 and 10. By the arrangement illustrated elevation of the form inking roller out of contact with the horizontal support is assured when the device is at rest so that the roller will not press upon the support to its own injury. When the support is the inking plate, which is usual, the handle is assured elevation out of contact therewith to prevent it from being spotted with ink. In the construction shown in Fig. 4 the projections 8 and 10 find their counterparts in the projections 8¹, 10¹ that are provided upon the base of the handle 4 rather than upon the ends 3 of the frame as illustrated in Figs. 1, 2 and 3. I desirably employ two distributing rollers 11 each having a shaft 11¹ loosely operating in a pair of openings 12, 13 that are provided in the end portions 3 of the frame upon opposite sides of the general plane occupied by the handle and the axis of rotation of the form inking roller. The distributing rollers are freely movable toward and from the handle and the form inking roller, such movement being permitted by said openings. Removal of the distributing rollers from the form inking roller occurs when the device is placed at rest. The distributing rollers are desirably light and are preferably made of wood whereby the entire structure is lightened and the form inking roller is not unduly pressed upon thereby. I do not wish to be limited, however, to the material of which the distributing rollers are made.

At least one and preferably both openings 12, 13 of each pair has, in the construction of Figs. 1, 3 and 5, two sides 14, 15 generally oblique to the general plane occupied by the handle and the axis of rotation of the form inking roller, one side extending toward said plane away from the form inking roller and the other side away from said plane and also from said form inking roller. By this construction of said openings the distributing rollers fall away from the form inking roller when the device is at rest whereby the weight of the distributing rollers is then relieved from the form inking roller to prevent the form inking roller from becoming impaired while the device is idle. In the construction shown in Fig. 4 the external sides of said openings are substantially parallel with the aforesaid plane but I prefer the construction illustrated in Figs. 1, 3 and 5. The openings are preferably triangular in shape but I do not wish to be limited to this characteristic.

While I have herein shown and particu-

larly described the preferred embodiment of my invention I do not wish to be limited to the precise details of construction shown as changes may readily be made without departing from the spirit of my invention, but having thus described my invention I claim as new and desire to secure by Letters Patent the following:—

1. A hand operated proofing inker including a form inking roller; a frame in which said roller is mounted to turn; a handle upon the frame, there being openings in end portions of the frame between the form inking roller and the handle; and a distributing roller having a shaft loosely disposed in said openings and in which, openings said shaft is free to move toward and from the handle and the form inking roller. 75 80

2. A hand operated proofing inker including a form inking roller; a frame in which said roller is mounted to turn; a handle upon the frame, there being two pairs of openings in end portions of the frame and upon opposite sides of the general plane occupied by the handle and the axis of rotation of the form inking roller; and two distributing rollers each having a shaft loosely operating in a pair of openings and in which openings said shafts are freely movable toward and from the handle and the form inking roller. 95

3. A hand operated proofing inker including a form inking roller; a frame in which said roller is mounted to turn; a handle upon the frame, there being openings in end portions of the frame between the form inking roller and the handle; and a distributing roller having a shaft loosely operating in said openings and in which openings said shaft is movable toward and from the handle and the form inking roller, sides of said openings adjacent the form inking roller being generally oblique to the general plane occupied by the handle and the axis of rotation of the form inking roller and extending away from the form inking roller whereby the distributing roller is free to descend from the form inking roller when the device is at rest.

4. A hand operated proofing inker including a form inking roller; a frame in which said roller is mounted to turn; a handle upon the frame, there being two pairs of openings in end portions of the frame and upon opposite sides of the general plane occupied by the handle and the axis of rotation of the form inking roller; and two distributing rollers each having a shaft operating in a pair of openings and in which openings said shafts are movable toward and from the handle and the form inking roller, sides of said openings of each pair adjacent the form inking roller being generally oblique to said plane and extending away from the form inking roller. 125

5. A hand operated proofing inker includ- 130

- ing a form inking roller; a frame in which said roller is mounted to turn; a handle upon the frame, there being two pairs of openings in end portions of the frame and 5 upon opposite sides of the general plane occupied by the handle and the axis of rotation of the form inking roller; and two distributing rollers each having a shaft operating in a pair of openings and in which 10 openings said shafts are movable toward and from the handle and the form inking roller each of said openings having two sides generally oblique to said plane, one extending toward said plane away from the form 15 inking roller and the other away from said plane and also from said form inking roller.
6. A hand operated proofing inker including a form inking roller; a frame in which said roller is mounted to turn; a handle 20 upon the frame, there being openings in end portions of the frame between the form inking roller and the handle; and a distributing roller having a shaft operating in said openings and in which openings said shaft is 25 movable toward and from the handle and the form inking roller, each of said openings having two sides generally oblique to the general plane occupied by the handle and the axis of rotation of the form inking roller, 30 one extending toward said plane away from the form inking roller and the other away from said plane and also from said form inking roller.
7. A hand operated proofing inker including a form inking roller; a frame in which 35 said roller is mounted to turn; a handle upon the frame, there being openings in end portions of the frame between the form inking roller and the handle; and a distributing roller having a shaft loosely operating in 40 said openings, a side of at least one of said openings adjacent the form inking roller being generally oblique to the general plane occupied by the handle and the axis of 45 rotation of the form inking roller and extending away from the form inking roller whereby the distributing roller is free to descend from the form inking roller when the device is at rest.
- 50 8. A hand operated proofing inker including a form inking roller; a frame in which said roller is mounted to turn; a handle upon the frame, there being two pairs of 55 openings in end portions of the frame and upon opposite sides of the general plane occupied by the handle and the axis of rotation of the form inking roller; and two distributing rollers each having a shaft operating 60 in a pair of openings, one side of at least one of said openings of each pair adjacent the form inking roller being generally oblique to said plane and extending away from the form inking roller.
9. A hand operated proofing inker including a form inking roller; a frame in which 65 said roller is mounted to turn; a handle upon the frame, there being two pairs of openings in end portions of the frame and upon opposite sides of the general plane occupied by the handle and the axis of rotation of the form inking roller; and two distributing rollers each having a shaft operating 70 in a pair of openings, at least one opening of each of said pairs having two sides generally oblique to said plane, one 75 extending toward said plane away from the form inking roller and the other away from said plane and also from said form inking roller.
10. A hand operated proofing inker including a form inking roller; a frame in which 80 said roller is mounted to turn; a handle upon the frame, there being openings in end portions of the frame between the form inking roller and the handle; and a distributing roller having a shaft operating in 85 said openings, at least one of said openings having two sides generally oblique to the general plane occupied by the handle and the axis of rotation of the form inking roller, 90 one extending toward said plane away from the form inking roller and the other away from said plane and also from said form inking roller.
11. A hand operated proofing inker including a form inking roller; a frame in which 95 said roller is mounted to turn; a handle upon the frame, there being openings in end portions of the frame between the form inking roller and the handle; and a distributing roller having a shaft operating in 100 said openings, at least one of said openings being sufficiently large loosely to receive the adjacent end of the shaft to permit the distributing roller freely to move toward and from 105 the handle and the form inking roller.
12. A hand operated proofing inker including a form inking roller; a frame in which said roller is mounted to turn; a handle upon the frame; and a distributing roller 110 having a mounting loosely holding the distributing roller and permitting movement thereof away from the form inking roller when the device is placed at rest.

In witness whereof I hereunto subscribe 115
my name this fifth day of June, A. D. 1917.

HORACE W. HACKER.
